CLAIM

The ornamental design for an anti-fatigue mat, as shown and described.

DESCRIPTION

FIG. 1 is a front perspective view of an anti-fatigue mat, showing our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

FIG. 8 is a perspective view thereof, shown in an alternate position.

The broken lines in the drawings depict the boundary of the claim and form no part of the claimed design.
